UNITED STATES PATENT OFFICE.

SEBASTIAN MACK, OF MINNEAPOLIS, MINNESOTA, ASSIGNOR TO MAGGIE MACK, OF MINNEAPOLIS, MINNESOTA.

SIGNAL FOR AUTOMOBILES.

Application filed September 18, 1926. Serial No. 136,335.

My invention relates to signals for automobiles, and more particularly to signals for use with closed automobiles. An object is to provide a device of this character which 5 may be readily operated by the driver from his seat without the necessity of extending one of his hands from the side of the vehicle, or opening one of the doors thereof to indicate the manner in which he is going to 10 drive the automobile such as in turning and in stopping. Another object is to provide a device of this character which can be readily installed on automobiles of various makes. Another object is to provide a device of this 15 character which is simple in construction and economical to manufacture and yet extremely efficient for the purpose for which it is intended.

The full objects and advantages of my 20 invention will appear in connection with the detailed description thereof, and the novel features of my inventive idea will be particularly pointed out in the claims.

In the accompanying drawings which illustrate a practical embodiment of my invention,—

Fig. 1 is a rear elevational view of the device showing it secured to a post of an automobile. Fig. 2 is a view in section on the line 2—2 of Fig. 1. Fig. 3 is a view in vertical section on the line 3—3 of Fig. 5. Fig. 4 is an elevational view of the inner side of the device. Fig. 5 is a view in vertical section on the line 5—5 of Fig. 3. Fig. 6 is a 35 fragmentary view in section on the line 6—6 of Fig. 5. Fig. 7 is a fragmentary view in section on the line 7—7 of Fig. 5.

Referring to the drawings, the numeral 10 designates an open-sided or U-shaped casing 40 which is closed at the top by a curved member 12. The casing 10 together with an angle strip 14 constitutes a support for the signal. The strip 14 is secured to a post P of a closed automobile by screws 16 passing through holes 18 in one of the angle members of the strip 14. The other angle member of this strip is provided with transverse slots 20 as shown in Fig. 4. Bolts 22 pass through these slots and through holes 20 in the inner wall of the casing 10. It will be understood that the provision of the slots 20 is for the purpose of securing the casing 10 in a vertical position regardless of whether or not the post P is exactly in a vertical position or is in an inclined position.

The signalling portion of the device includes an arm which consists of a tubular member 24 which at its inner end is secured to a base member 26 having a rounded wall 28. Secured to the base member 26 is a trunnion 30 adapted to rotate in two forks 32 secured within the casing 10 at opposite sides thereof. A hollow head member 34 is secured to the outer end of the tubular member 24 and this head member has slots or windows 36 in its front and rear sides. Within the member 34 there is an electric light bulb 37 held in a socket 38 carried by the outer member of the tubular member 24. A wire 40 extends from the socket member 38 to a contact 70 member 42 insulatively mounted on the base member 28. The contact member 42 is arranged to slide on a curved contact strip 44 insulatively mounted on the inside of the casing 10. The battery of the automobile 75 is connected by a wire 46 with the contact strip 44. The contact member 42 moves off the strip 44 when the arm is in its downward position. For other positions of the arm, the two contacts are in engagement so 80 that the lamp is lighted by current from the battery. In order to releasably hold the signal arm in different outward positions, the outside of the rounded wall 28 is provided with depressions 48 adapted to receive 85 a spring-pressed ball 50 carried by the curved top member 12. The base member 26 opposite the rounded wall 28 carries a lug 52 to which the upper end of a link 54 is pivotally attached. The lower end of the 90 link 54 is pivotally attached to the crank arm 56 carried by a rotatable member 58 mounted in a rounded opening formed in a casting 60, the member 58 being held in said opening by a cotter-pin 62 as shown in Fig. 95 5. The rotatable member 58 contains a recess across which a pin 64 extends as shown in Fig. 2. A rod 66 passes rotatably through a hole in the post P. The outer end of the rod 66 is reduced to a less thickness than that of said recess and is provided with a hole through which the pin 64 passes, the hole being larger than the pin so that the device will function regardless of the angle at which the rod 66 passes through the post. The connection is, therefore, in the nature of a universal joint. A handle member 68 is secured to the inner end of the rod 66 so that the driver may readily 100 operate the signal device.

The operation and advantages of my invention have already been largely set forth. The signal arm is normally housed in the casing 10 in depending position as indicated at 24 in Fig. 1. When the driver wishes to signal, he turns the handle 68 thereby bringing the signal arm into desired outward positions such as indicated at 24' and 24'' in which positions the arm is temporarily held by the ball 50. An important advantage of my invention consists in the fact that when not in use for signalling, the signal arm is housed in the casing 10 with no outstanding portion to confuse persons who are relying on the signal as an indication of the manner in which the automobile is to be driven. Another advantage consists in the fact that the device may be readily attached to a post of any make of automobile regardless of the size or inclination of the post. It is apparent that the angle strip 14 may be placed with either end up. It is, therefore, possible to place the strip 14 so that its outwardly extending flange will project from

the middle portion of the inner wall of the 25 casing 10 or to place it so that the outwardly extending flange will project from near the edge of such wall. My device contains no gears, pinions or racks, and hence the expense of cutting teeth on such device is 30 avoided.

I claim:

A signal for automobiles comprising a right angle strip one of whose angle members is adapted to be secured to the front 35 face of a corner post of the automobile and the other of whose angle members contains horizontal slots, a support adjustably attached to said angle strip by means of said slots, a signal arm pivoted to said support 40 and adapted to lie adjacent and parallel to the latter, and connections extending from said arm to the inside of the automobile whereby said arm may be swung into outward position. 45

In testimony whereof I hereunto affix my signature.

SEBASTIAN MACK.
